UNITED STATES PATENT OFFICE.

WALTER C. TRELOAR, OF MITCHELL, SOUTH DAKOTA.

TILING TARGET.

Application filed April 27, 1921. Serial No. 464,834.

To all whom it may concern:

Be it known that I, WALTER C. TRELOAR, a citizen of the United States, residing at Mitchell, in the county of Davison and State 5 of South Dakota, have invented certain new and useful Improvements in Tiling Targets, of which the following is a specification.

This invention relates to new and useful 10 improvements in measuring instruments, more particularly to devices for determining the depth of grades and ditches, known as tiling targets, and the primary object of the invention is to provide a device of this 15 character which can be set up for operation by one man and quickly and readily applied to use and the depth and grades determined.

Still another object of the invention resides in providing a device of this character 20 which may be made of wood, metal or wood and metal, as desired, and the staff of which is provided with graduations, thus eliminating the necessity of using a rule separately in connection therewith.

Another object of the invention resides 25 in providing a device comprising an upright and levels adjustably carried thereon, said levels being adapted for support on the upright and on surveyors' depths hubs 30 disposed in the ground.

A still further object resides in providing a device which is simple and durable in construction, inexpensive to manufacture, and one which is very efficient in operation.

With these and other objects in view my 35 invention consists in the novel features of construction, combination and arrangement of parts as will be hereinafter referred to and more particularly pointed out in the 40 specification and claims.

In the accompanying drawing, forming a part of this application—

Figure 1 is a side elevation of a device 45 constructed in accordance with my invention and applied to use; the dotted lines indicating attachment in using the device for the deep ditch digging.

Fig. 2 is a perspective view of one of the 50 levels removed;

Fig. 3 is a side elevation of a modification of my invention;

Fig. 4 is a perspective view of the clamp removed.

In describing the invention I shall refer 55 to the drawing in which similar reference characters designate corresponding parts

throughout the several views, and in which 1 designates an upright formed preferably of wood and provided with graduations on two sides thereof, the one being in feet and 60 inches, and the graduations on the opposite side being in tenths and hundredths, the latter not being disclosed in the drawing.

One side edge of the upright at its lower end is cut away to receive therein a metal 65 prong or the like 2, which is secured in place by means of screws so that the outer face of the prong is flush with the outer face of the upright, and this prong extends some distance below the lower end of the upright 70 so as to support the latter above the ground, which is designated in the drawing as 3. The lower end of the upright as shown in Fig. 1, is supported on a surveyor's depth 75 hub 4.

The depth at the hub is known and it is therefore only necessary to operate in connection with the graduations and the staff or upright 1. A level 5 is provided which has the metal arms or projections 6 thereon, said arms being adapted for contact with the front and rear faces of the upright 1, and a thumb-screw 7 is applied in connection with the arms 6 so as to lock the latter in frictional contact with the upright at 80 85 any desired and adjusted position thereon.

An angular brace 8 is carried on the under face of the level and a thumb-screw 9 carried at the outer end thereof is adapted for engagement with the side edge of the upright 1 so that the level may be held in its 90 adjusted position and properly supported. Usually, three of these targets are used in tiling and in looking over the levels one may readily determine whether the targets 95 are accurately set.

In using the device disclosed in Fig. 1 it is placed upon the level of the ground with the upright 1 supported in the vertical position, and as an illustration let it be supposed that 100 the ditch to be dug will be five feet. The level 5 is then adjusted to a point to correspond to this height or to the first graduation above the surveyor's hub 4. Three of these devices are used and are arranged at 105 predetermined distances along the ditch to be dug. With the devices arranged as stated, the operator sights over the level 5 and sighting over a six foot staff and over these levels he can readily indicate whether or not 110 the ditch has been dug to the required depth. Should the staff stand above the levels then

he would know that the ditch has not been dug to the required depth.

In digging ditches of a greater depth, the level 12 is employed as shown in the modification in Fig. 3 of the drawings. In this instance it is adjusted by means of the metal arms 13 and the thumb screw 14 similar to the arms 16 and the thumb screw 7 of the level 5 along the staff 1 and this staff is supported in the ditch while the level 5 acts as a brace for supporting the upper end of the upright 1. Anchoring elements 10 and 11 are engaged with the brace level 5 and driven into the ground to hold the device in a perpendicular position. With the parts in this position the level 12 is used in the same manner as the level 5 as set forth above.

From the foregoing description of the construction of my improved device, the operation thereof will be readily understood and it will be seen that I have provided a simple, inexpensive and efficient means for carrying out the objects of the invention.

While I have particularly described the elements best adapted to perform the functions set forth, it is obvious that various changes in the form, proportion and in the minor details of construction may be resorted to without departing from the spirit or sacrificing any of the principles of the invention.

Having thus described my invention, what I claim as new and desire to secure by Letters Patent is:

1. A device of the class described comprising an upright having graduations thereon, a level, means for slidably sup-

porting said level on said upright, an angular bracing member carried by said level and designed for contact with the side edge of said upright, and means carried by the bracing member for contact with the upright to adjust the level with respect to the latter.

2. A device of the class described having graduations thereon, a level slidably supported on said upright, means for retaining said level in various adjusted positions on the upright, an angular bracing member carried by the level and adapted to contact with the side edge of said upright, and a thumb-screw carried on said bracing member for contact with the upright to adjust the level with respect to said upright.

3. A device of the class described comprising a graduated standard, supporting means associated therewith, a level having arms extending from the sides thereof and adapted to receive said standard therebetween, and a clamp associated with the free ends of said arms to hold said level in its adjusted position on said standard.

4. A device of the class described adapted for use in deep ditch digging, comprising a graduated standard adapted to extend vertically into said ditch, a level adjustably carried by the lower end of said standard, a brace adjustably carried by the upper end of said standard, and means associated with said brace and adapted to be driven into the ground for holding said standard in a vertical position.

In testimony whereof I affix my signature.

WALTER C. TRELOAR.
